UNITED STATES PATENT OFFICE.

JOHN O. CARREY, OF ST. LOUIS, MISSOURI, ASSIGNOR TO CARREY ROTARY ENGINE COMPANY, OF ST. LOUIS, MISSOURI, A CORPORATION OF MISSOURI.

TURBINE.

1,415,219.

Specification of Letters Patent. Patented May 9, 1922.

Application filed August 19, 1919. Serial No. 318,577.

To all whom it may concern:

Be it known that I, JOHN O. CARREY, a citizen of the United States, residing at the city of St. Louis and State of Missouri, have 5 invented a new and useful Turbine, of which the following is a specification.

This invention relates to improvements in turbines, and consists in the novel design, arrangement and combination of parts here-10inafter described.

An object of the invention is to provide a turbine, having a rotor arranged for propulsion by injection of steam in a plurality of series of expansion pockets, whereby the 15 force of the steam is utilized according to its normal line of expansion.

Another object of the invention is to provide, in a turbine, a novel form of injectors for introducing the steam pressure into the 20 expansion pockets of the rotor.

Another object of the invention is to provide a turbine with the injectors so arranged as to balance the lateral pressure on the rotor, whereby it is relieved from lateral 25 strain, thereby permitting the use of high pressure without a binding effect on the power shaft.

Another object of the invention is to provide means in a turbine, whereby the steam 30 pressure may be rapidly condensed after the propulsive force thereof has been expended in the operation of the rotor.

Additional advantages from the construction will be apparent without specific men-35tion from the following disclosure of the invention taken in connection with the accompanying drawings, in which:

Fig. 1, is a side elevation of the turbine, embodying the invention.

Fig. 2, is an end elevation of the turbine.

Fig. 3, is a vertical section through the turbine casing, showing in further detail, the construction of the rotor.

Fig. 4, is an enlarged fragmentary view, 45 illustrating particularly the injectors in association with the rotor.

Fig. 5, is an inside elevation of one of the side plates of the turbine.

Fig. 6, is a cross section through the tur-50bine, and

Fig. 7, is a detailed fragmentary view of a section of one of the side plates, illustrating particularly the construction of one of the communicating passages from one series of 55 expansion pockets to the other series of expansion pockets.

As illustrated in the drawings, the construction includes a casting formed with a base 1 which supports, in integral connection, a substantially annular casting 2, which forms the side wall of the stator. At the bottom of the casting 2, and integrally formed therewith, is a discharge conduit 3 for the outward passage of the condensed steam. It will be observed that the casting 65 3 is enlarged in its circular formation to a slight degree near the bottom so as to provide a free outlet for the condensed steam.

The casting 2 is provided with annular flanges 4 on each side. The flanges 4 are 70 preferably formed integral with the casting 2. Side members 5, having enlarged bosses 6, are secured by a series of bolts 7 to the flanges 4.

The side members together with the casting 75 2 form the enclosed stator case of the turbine. At the center of the bosses 6 are bearing portions 8 for the main power shaft 9.

The rotor of the turbine comprises a hub 80 10 fast on the power shaft 9 and mounted within the stator case. Attached to the periphery of the hub 10, and preferably formed integral therewith, are a spaced series of angular vanes 11. The intervals between the 85 vanes 11 form pockets 12.

An annular plate 13, having a series of angular vanes 14, is fitted over the vanes 11, and is secured thereto in any suitable manner. The plate 13 constitutes a closing 90 wall for the pockets 12. The vanes 14 are so disposed on the plate 13 and the adjustment of the plate 13 is such, that the vanes overlie the intervals between the vanes 11. Thus, a second series of pockets are provided in 95 the rotor for the reception of steam from the first series of pockets after the expansive force of the steam has been utilized in the first series.

An annular plate 15, supporting a series 100 of angular vanes 16, is fitted over the second series of vanes 14 in a similar manner to the way in which the plate 13 is fitted over the vanes 11. The vanes 16 are so disposed on the plate 15 and the plate 15 is so adjusted 105 with respect to the vanes 14 that the vanes 16 overlie the intervals between the vanes 14. Thus, a third series of pockets is provided for the reception of the steam from the second series of pockets after the expansive force of steam has been utilized in 110 the pockets of the second series of pockets.

An annular band 17 is fitted over the vanes 16, the band 17 carrying a series of curved vanes 18 which function to expel the condensed steam discharged from the third series of pockets. The condensed steam passes from the third or outer annular series of pockets through grooves 27 and is expelled by the vanes 18 through a discharge pipe 29.

10 The operating fluid is supplied through two supply pipes 19 which enter the enlarged hub portions 6 of the side members. Said hubs contain annular chambers 20 into which the pipes 19 open.

15 Injectors comprising nozzles 21, fitted within tapering cases 22, are so arranged as to inject the steam from the chambers 20 into the pockets 12 through adjustable passages 23 threaded into the side members.

20 The passages are so disposed that the steam will pass into the pockets 12 at a downwardly inclined tangential angle. The injectors have, extending laterally from the cases 22, aspirator nozzles 24; the aspirator nozzles being so placed that when the steam is injected through the passages 23, the aspirator openings will be in communication with the next following pocket 12 in the rotor. The injectors are arranged in pairs

25 on each side of the rotor and upon equally spaced circumferential points. The impelling force is thus introduced into the rotor in such a manner that the forces are balanced, preventing lateral strain on the rotor.

30 The arrangement and action of the injectors may be better understood by reference to Fig. 4, in which one pair of injectors are shown in association with a segment of the rotor. When steam passes through the in-

35 jectors it is discharged from the pair of nozzles at a downwardly inclined angle from either side of the rotor, the jets of steam from both injectors meeting at the apex of the vanes 11. The steam passing through the nozzles 21, which are enclosed within the case 22, produces an aspirator effect in the nozzles 24.

40 As the nozzles 24 are oppositely disposed, and are in communication with the pocket 12 following the pocket in which the jets of steam enter from the nozzle 21, a suction will be created in such pockets as they come in communication with the aspirator nozzles 24. There is thus produced, a double power effect, the one resulting from the impinging action of the jets of steam against the vanes 11, and the other from the suction created by the aspirator nozzles 24 in the pockets in communication with such nozzles 24.

45 The injectors are arranged at intervals in pairs and any desired number of pairs may be provided, the embodiment illustrated in the drawings comprising three pairs.

50 In the inner walls of the member 6 and 55 arranged in laterally alined pairs, are chan-

nels or grooves 25 which communicate with the pockets 12 at their lower end and with the pockets in the next series at their upper end. The grooves or channels 25 are concave on their longitudinal and transverse axes and are arranged in pairs at equally spaced intervals between the injectors for the inner series of pockets. Thus, in the operation of the turbine, the steam first expands in the pockets 12, and as each pocket 75 passes beyond the injector, the steam is forced outwardly in the grooves 25 and into the pockets in the second series. The incoming force of the steam injected into the pockets of the second series impinges against 80 the vanes, increasing the power of the forward rotation of the rotor.

A second series of grooves 26, of a similar construction and arranged in the intervals between the first series of grooves 25 provide communication between the pockets in the second series and the pockets of the third series, so that after the steam has expanded in the pockets of the second series it is forced into the pockets of the third series 90 as they come into registration with the grooves 25, where the propulsive action of the steam is repeated in the pockets of the third or outer series.

A third series of similarly formed grooves 95 27 arranged in pairs in the side members, are provided for communication between the pockets in the outer series, and the space between the ring 17 and the stator case.

An inlet opening 28 is provided through 100 the side members of the stator case for the admission of water into the space intermediate of the ring 17 and the wall 2 of the stator case.

The incoming water is distributed by the 105 plates 18 throughout the space between the rotor and the stator case and serves to condense the volume of steam entering this space. The plates 18 maintain a constant suction for withdrawing the steam from the 110 third series of pockets and discharging the condensed steam from the discharge conduit 3. The condensed steam is forced outwardly through a discharge pipe 29 and may be returned to the boiler for use. The rapid 115 condensation of the steam in the outer space between the stator case and the rotor sets up a vacuum or suction action generating a pulling force or power in the outer series of pockets.

120 It will be observed that the construction utilizes the full propelling and suction force of the steam in the inner series of pockets and that the steam expands outwardly along the normal line of expansion into the second and third series of pockets, exerting in each series a propelling force.

125 It will be understood that the number of series of pockets may be increased, and also that the number of pockets may be increased, 130

and that the construction may be modified in other particulars without departure from the spirit and scope of the invention. I do not limit myself therefore, to the exact construction shown and described, but what I claim and desire to secure by Letters Patent, is:—

1. In a turbine, the combination of a stator case, a power shaft journaled in the case, and a rotor mounted on said power shaft having pockets therein, open at the sides, with an injector comprising an inlet nozzle arranged to inject a jet of steam into the pockets in the rotor, and an aspirator 15 nozzle in connection with said first-named nozzle in communication with the pockets in the rotor for producing a suction in the pockets.

2. In a turbine, the combination of a rotor 20 having vertical pockets open at the sides, a case encasing said rotor, with a pair of injecting nozzles entering said case and disposed so as to direct jets of steam from opposite points through the side openings of the pockets, and an aspirator nozzle in connection with each of said first-named nozzles to communicate in succession with the pocket following the pocket receiving a charge from the injecting nozzles.

3. A turbine, comprising a stator case, a rotor mounted in said case, angular vanes on said rotor arranged with the apex thereof on a central line around the periphery of said rotor, nozzles including an injector 35 opening directed in a downwardly inclined tangential direction to inject jets of steam against certain of said vanes, and aspirator nozzles in connection therewith, opening into the interval between certain of said vanes.

4. In a turbine, the combination with a stator case, of a rotor mounted in the stator case, annular series of pockets in the rotor all of which extend entirely across the rotor the full length of the interior of the stator case, 45 means for injecting steam into the inner series of pockets from opposite sides of the rotor, and means for creating a vacuum successively in said series of pockets.

5. In a turbine, the combination with a 50 stator case, and a rotor having vertical pockets therein with the sides thereof open, of an aspirator injector device arranged to introduce steam pressure successively in the pockets and to produce suction action successively in the following pocket.

6. In a turbine, the combination of a 55 stator case, a rotor mounted in the case having pockets comprising angular front and rear walls and circular top and bottom walls, 60 steam supply passages entering both sides of the stator case, and a plurality of injector devices having aspirator nozzles in connec-

tion therewith, arranged to introduce steam pressure from opposite sides into the pockets, and to create a vacuum by withdrawing 65 pressure from both sides of said pockets.

7. A turbine, comprising a stator case, a shaft extending through and journaled for rotation in said case, a rotor attached to said shaft in said case, concentric annular series 70 of pockets in and extending the full width of said rotor, a number of steam injection passages arranged to inject steam from opposite sides of the rotor into the inner series of pockets, passages for conducting the 75 steam successively into the remaining series of pockets, passages for conducting the condensed steam from the outer series of pockets into the stator case, and means supported around and driven by the rotor for expelling the condensed steam from said case. 80

8. A turbine, comprising a circular case and shaft journaled in said case, a series of annular supports arranged in spaced relationship, transverse angular walls dividing 85 the space between said supports into pockets, a series of curved plates carried by the outer one of said supports, said plates constituting fan blades to exhaust the pressure from said case, means for introducing steam 90 pressure into the inner series of pockets, and vertical passage ways for transferring the steam pressure from the pockets of one series to the next outwardly adjacent series 95 of pockets.

9. A turbine, comprising a case including a circular plate and side walls, a shaft, a hub supported by the shaft, a number of annular series of radially extending angularly inclined walls extending the full length of the interior of said case, annular partition walls separating said radially extending walls so as to form a plurality of annular series of pockets each of which extends the full length of the interior of said case, means 100 for injecting operating fluid into the inner series of pockets, and passages through the side plates for conducting the pressure from the inner series to the outer series of pockets. 105

10. A turbine, comprising a case including a circular plate and side walls, a shaft, a hub supported by the shaft, a series of radially extending angularly inclined walls, annular partition walls separating said radially extending walls so as to form a plurality of staggered series of pockets, means for injecting operating fluid into the inner series of pockets, passages through the side plates for conducting the pressure from the inner 110 series to the outer series of pockets, and a 115 series of fan blades carried by the outer annular partition wall for exhausting pressure from the case.

JOHN O. CARREY.
